UNITED STATES PATENT OFFICE.

HENRY A. OWEN, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

TENSION DEVICE.

Application filed September 5, 1925. Serial No. 54,658.

To all whom it may concern:

Be it known that I, HENRY A. OWEN, a citizen of the United States, residing at Whitinsville, in the county of Worcester and Commonwealth of Massachusetts, have invented certain new and useful Improvements in Tension Devices, of which the following is a specification.

My invention relates to tension devices for 10 yarn and thread winding machines.

The principal object of the invention is to provide a device in which the tension of the yarn may be regulated with precision and any desired amount of tension maintained without subjecting the yarn to undue strains.

Another object of the invention is to provide a construction whereby a desirable cleaning of the yarn is effected. The principle of the combination will be made apparent from the illustrative embodiment shown in the drawing, wherein—

Figure 1 is a cross section of a portion of a spooler of conventional type showing my 25 improved tension device incorporated therewith;

Figure 2 is a plan view of the tension device;

Figure 3 is a sectional elevation on line 30 3—3 of Figure 2;

Figure 4 is an end elevation of the tension device; and

Figure 5 is an enlarged sectional view 35 showing the relative positions of the tension disks and the supporting bearing of the lower disk.

Referring to the drawings, Figure 1 shows the yarn 2 being drawn from a stationary bobbin 4 through my improved tension device and then wound on the rotating spool 5.

The tension device which I have shown herein comprises a base member 7 which is 40 adjustably mounted on some part of the machine preferably, as is shown, on the traversing rod 8. The yarn 2 is drawn from the bobbin 4 through the notch or guide 6 on the outer edge of the base member 7 and thence between the surfaces of two rotatable 45 disks, the resistance which they offer to rotation imparts a tension to the yarn. The lower disk 9 made of thin flexible metal is 50 rotatable on a bearing 10 formed in the upper surface of the base member 7. The up-

per disk 11, superimposed on the lower disk 9, is slidably and rotatably mounted on a pin 12 whose axis is at right angles to the upper face of the base member 7. The pin 12 is fastened to the bracket 13 which is in a stationary relation with the upper surface 55 of the base member 7. The position of the pin 12 is such that the centre of rotation of the upper disk 11 is offset from the centre of rotation of the lower disk 9. This eccentricity of the centres of rotation between 60 the disks is an essential factor in effecting the cleaning of lint and bunches from the yarn in its passage between the disks. To prevent the matter that is thus removed from the yarn from accumulating and obstructing the motion of the disks the lower disk 9 is provided with a centrally located circular aperture 14 registering with a circular aperture 15 in the base member 7 through which the waste matter finds a passage 65 to the floor below.

Additional tension to the yarn may be had by the use of one or more weights 16 slidably and rotatably mounted on the pin 12 and exerting pressure by their weight on the 70 top of the hub of the disk 11.

To facilitate the threading of the yarn between the surfaces of the disks the upper disk has upwardly flaring edges which provides a crevice between the surfaces of the 75 disks into which the yarn falls from the inclined end 17 of the bracket 13.

I claim:

A yarn tension device comprising a base, a circular aperture in the base, a disk rotatably mounted in a bearing concentrically formed with the aperture in said base, a centrally located circular aperture in said disk registering with the aperture in the base, a second disk superimposed on the 90 first disk, a pin whose axis is at right angles to the upper face of the base and offset from the centre of the aperture in the first disk, a bracket in stationary relation with the base and supporting the pin, the second disk rotatably and slidably mounted thereon, a notch in the base guiding the yarn between the surfaces of the two disks, and an inclined member to facilitate the threading of the yarn.

In testimony whereof, I have signed this specification.

HENRY A. OWEN.
